HAROLD A. SWAN, OF CORONADO, CALIFORNIA.

PORTABLE SANDING MACHINE.

Application filed September 29, 1927. Serial No. 222,866.

This invention relates to improvements in sanding machines and has as its general object to provide a machine which will be highly efficient in operation and which will operate 5 to abrade or sand the work to be dressed, in a highly efficient manner and with the expenditure of much less time than is ordinarily required in performing this task.

Another object of the invention is to provide a sanding machine of compact construction and operated through the medium of an electric motor, the machine being adapted to be conveniently manipulated and guided over the surface of the work to be dressed.

Another object of the invention is to provide a sanding machine which may be readily converted for use either by the employment of an endless belt as the abrading medium, or by utilizing one of the rolls over which the 20 belt is trained and by which it is driven, as the abrading means, so that the machine may be conveniently and readily converted from a belt sander to a cylinder sander, and vice versa, depending upon the character of the 25 work.

Another object of the invention is to provide novel means for transmitting power to the abrading element of the machine, whether it be a belt, or one of the rolls about which the 30 belt is trained and from which the belt is driven.

Another object of the invention is to provide novel means for maintaining the lower or working stretch of the abrading belt in flat, 35 and even contact with the surface of the work to be dressed, where the belt is employed as the abrading medium, and to provide for utilization of this means as a means for steadyng and supporting the machine for 40 movement over the surface of the work, when the belt is removed and the drive or power roll of the machine is employed as the abrading medium.

While the accompanying drawings and the 45 description which is to follow, constitute a disclosure of the preferred embodiment of the invention, it will be understood that various changes may be made within the scope of what is claimed.

In the accompanying drawings:

Fig. 1 is a side elevation of the sanding machine embodying the invention;

Fig. 2 is a top plan view thereof;

Fig. 3 is a vertical longitudinal sectional view through the machine;

Fig. 4 is a vertical transverse sectional view taken substantially on the line 4—4 of Figure 3 looking in the direction indicated by the arrows;

Fig. 5 is a similar view on the line 5—5 of Figure 3 looking in the direction indicated by the arrows;

Fig. 6 is a vertical transverse sectional view taken substantially on the line 6—6 of Figure 1 looking in the direction indicated by the arrows;

Fig. 7 is a front elevation of the machine, a part being shown in section.

The machine embodying the invention includes a body casting which includes a base 1, an electric motor casing 2 which is integral with the base 1 and located substantially at the center of the upper side thereof, and a gear case 3 which is likewise cast integral with the base and located at the rear thereof and in rear of the motor casing 2. The electric motor of which the casing 2 constitutes a part, is of any approved type, and the conductor wires for the motor, indicated by the numeral 4, are led to the motor through the forward side of the casing 2, from any suitable source of current supply. Ears 5 are formed integrally with the opposite sides of the base 1 at the rear end thereof, and a spindle 6 is fitted through bosses 7 formed upon the inner sides of the ears and threaded at one end as at 8 into one of the said bosses. A sleeve 9 is fitted onto the said spindle for rotation and supports the drive or power roll of the machine which is indicated by the numeral 10. The under side of the base 1 is recessed at the forward end of the base as indicated by the numeral 11, and a bearing member comprising a plate 12, is slidably adjustably disposed within the recess and is adapted to be adjusted in a forward and rearward direction through the medium of a screw 13 having right and left hand threads, one end of the screw being threaded into an opening 14 formed in an upstanding lug 15 formed integral with the upper side of the base 1, the other end of the screw being threaded through an opening 16 formed in an ear 17 upstanding from the plate 12 at the forward side of the

said plate, the said ear 17 working in a slot 18 formed to extend in a front to rear direction longitudinally within the said base 1 at the upper side and front of the recess 11 there-
5 in. Ears 19 project downwardly from the opposite ends of the plate 12, and a spindle 20 corresponding to the spindle 6, is mounted at its ends in the said ears 19 and has rotatably fitted thereon a sleeve 21 which supports a
10 roll which is indicated by the numeral 22 and which is of the same dimensions as the roll 10. A belt 23 is trained over the rolls 10 and 22 with its upper stretch travelling beneath the base 1 and its lower stretch travelling beneath
15 a shoe which is adjustably mounted beneath the base 1 as will presently be explained, it being understood at this point that the belt may be rendered taut by adjusting the screw 13 so as to move the bearing member 12 in a
20 forward direction, the screw being provided between its threaded end portions, with a knurled head 24 to facilitate such adjustment of the screw.

The belt 23 will have applied to its outer surface, a coating of any suitable abrading material such for example as sand or garnet, and it will readily be understood that the lower stretch of the belt constitutes the abrading stretch.

30 In order that motion may be imparted to the belt 23, means is provided which will now be described.

The means referred to above comprises a shaft 25 which is rotatably journaled at its ends in suitable bearings 26 upon the opposite side walls of the gear case 3, and this shaft has fixed upon it, midway between its ends, a worm gear 27 which is in mesh with a worm 28 fixed upon the shaft 29 of the motor 2, the motor shaft having its rear end ex-
35 tended longitudinally through the gear casing 3 and journaled in suitable bearings in said casing. Wheels 30 are fixed upon the shaft 25 at the under sides of the worm gear 27 and each of these wheels is provided with a rim 31 which is preferably of soft rubber and preferably formed with a number of con-
40 cave depressions 32 in its surface. As will be observed by reference to Figures 3 and 6 of the drawings, the rims 31 of the wheels 30 travel in frictional contact with the portion of the belt 23 which passes over the upper side of the roll 10 and in this manner motion is transmitted to the belt and roll, so as to effect
45 travel of the belt and cause the lower stretch thereof to act upon the piece of work to be dressed. It will be evident that inasmuch as the rim 31 of each wheel 30 is of soft rubber and is formed with the depressions 32, these
50 depressions constitute, in effect, vacuum cups which insure of a positive and steady appli-
cation of power through the medium of the rim 31, to the belt 23, and likewise the cups serve to remove particles of material which
55 might otherwise adhere to the surface of the

belt, and which particles are removed by the abrasive action of the lower stretch of the belt upon the surface of the work. Therefore the wheels 30 and their rims 31 constitute not only means for transmitting motion to the belt, but also as a means for freeing the belt from accumulations which would be liable to impair its efficiency as an abrading me-
60 dium.

In order that the lower stretch of the belt 75 23 may be held in snug and flat contact with the surface of the work to be dressed, means is provided for backing this stretch of the belt or in other words for holding it against upward flexing or displacement, and this 80 means includes a shoe which is indicated in general by the numeral 33 and comprises a body plate 34 to the under side of which there is applied and suitably secured, by adhesive or otherwise, a sheet 35 of felt or other ma- 85 terial found suitable for the purpose. The plate 34 is of oblong rectangular form and, as will be observed by reference to Figures 1, 3, 4 and 5, extends in a front to rear direction 90 in the space between the rolls 10 and 22 and is of a width slightly greater than the width of the belt 23, the lower stretch of the belt traveling beneath the shoe and in contact at its upper surface with the under surface of the sheet 35, as clearly shown in Figures 95 3, 4 and 5 of the drawings. It will be observed at this point that the under surface of the sheet 35 of the shoe 33 occupies the same horizontal plane as the under sides of the rolls 10 and 22, so that the lower stretch 100 of the belt 23 is not only held taut through adjustment of the screw 13 and the consequent adjustment of the roll 22 in a forward direction and away from the roll 10, but also by reason of the engagement of this stretch 105 against the sheet 35 which is rendered sub-stantially rigid through its attachment to the plate 34. The plate 34 has formed upon its upper side, near its forward end, a pair of 110 upstanding lugs 36 the upper sides of which are inclined downwardly and forwardly and provided with laterally outstanding tongues 37 which tongues work in grooves 38 provided between spaced ribs 39 formed upon the inner sides of depending side portions or 115 cheek pieces 40 which are integral with the base 1 and project downwardly therefrom as clearly shown in Figures 1, 3 and 4 of the drawings. Lugs 41 similar to the lugs 36 are formed upon the plate 34 near the rear end thereof and are provided with outstanding tongues 42 which are inclined down- 120 wardly as in the case of the tongues 37 and are guided in grooves 43 formed between spaced ribs 44 in turn formed upon the inner 125 sides of cheek pieces 45 which correspond to the cheek pieces 40, previously described and which therefore, as in the case of the said cheek pieces 40, depend from the opposite sides of the base 1. A pair of ears 46 is 130

formed upon the upper side of the plate 34 near the front thereof and between the lugs 36, and a bearing block 47 is swingingly mounted upon a rivet 48 which extends between the ears 46, and is provided with a threaded opening 49 into which is adjustably threaded the forward portion of a stem 50, this stem being provided, intermediate its ends, with an enlarged cylindrical head 51 having a series of sockets 52 arranged preferably in spiral alinement about the head and adapted to accommodate the end of a nail or any other pointed device whereby the head may be rotatably adjusted to correspondingly adjust the stem 50. The stem extends likewise rearwardly beyond the head 51, and this portion of the stem, at its extremity, is rotatably fitted in an opening 53 formed in an ear 54 which depends from the under side of a collar 55 which is pressed or otherwise secured upon a sleeve 56 which is rotatably fitted on a bolt 57 which is inserted through an opening in one of the cheek pieces 45 and threaded at its end into an opening in the other cheek piece. The end of the stem 50 which is rotatably mounted in the opening 53, is provided with spaced collars 58 which engage the front and rear sides of the ear 54 so as to prevent longitudinal displacement of the said end of the stem 50 in the opening in the said ear and yet provide for free rotative adjustment of the stem so as to effect longitudinal adjustment of the bearing block 47 and thus, in turn, effect a forward or rearward adjustment of the plate of the backing member or shoe 33. At this point it will be understood that when the shoe 33 is adjusted forwardly, the tongues 37 and 42 riding downwardly in and being guided by the grooves 38 and 43, respectively, will effect a downward displacement of the shoe 33, whereas a reverse adjustment of the shoe will result in elevation of the shoe. Therefore the screw stem 50 may be adjusted so as to effect adjustment of the shoe to cause the same to more or less firmly bear against the upper side of the lower stretch of the belt 23 and thus maintain this stretch of the belt flat and prevent upward sagging or distortion thereof when the lower or abrading side of the stretch is disposed upon the surface of the work to be dressed.

From the foregoing description of this embodiment of the invention it will be evident that there has been provided a sanding machine which is extremely simple and compact in its construction and which may be very conveniently employed in dressing work and in a manner to effect sanding of work more expeditiously than can be done by hand or by the use of other machines which do not possess the features of the present machine.

In the embodiment of the invention illustrated and described, travel is imparted to the belt 23 through direct contact of the yield-

able rims 31 of the wheels 30 with the portion of the belt which extends over the upper side of the roll 10, rotary motion being imparted to this roll, at the same time that travel is imparted to the belt, due to the firm engagement of the rims of the said wheels against the belt to have binding contact against the belt and similar contact of the belt against the said roll 10. It will likewise be evident that due to the formation of the depressions 32 in the rims 31, particles which might otherwise accumulate upon the abrading surface of the belt will be removed by suction.

Under some conditions it may be desirable, due to the character of the work to be dressed, or other conditions met with, to abrade the surface of the work through the medium of a rotary roll rather than through the passage of the stretch of an abrading belt over the work, and the present invention is peculiarly adapted to this adaptation of the machine illustrated inasmuch as, in such event, it is only necessary to remove the front roll 22 and belt 23, and apply a sheet of abrasive material about the surface of the roll 10, whereupon the machine may be moved over the surface of the work to be dressed in the same manner as though the belt were present, the roll, in this instance, acting upon the surface to dress the same, and the shoe 33 serving as a support for the machine so as to properly position the roll with respect to the surface of the work.

Having thus described the invention, what I claim is:

1. In an abrading machine of the class described, a body, an abrading medium operatively mounted thereon, a power shaft upon the body, and a friction wheel driven by the shaft and having a yieldable, cupped rim in frictional driving contact with the abrading medium.

2. In an abrading machine of the class described, a body, an abrading medium operatively mounted thereon, a power shaft upon the body, a wheel driven from the power shaft, and a rim of yieldable friction material upon the wheel in direct frictional driving contact with the abrading medium, the said rim having depressions in its friction surface for enhancing the frictional contact between the rim and the said abrading medium and for removing accumulations from the surface of the said medium through suction created by compression and expansion of the depression bearing portion of the rim.

3. In an abrading machine of the class described, a body, an abrading medium operatively mounted thereon, a motor mounted upon the body, a shaft mounted upon the body counter to the shaft of the motor, a gear upon the second mentioned shaft, a gear element upon the motor shaft coacting with the gear upon the second mentioned shaft, and spaced friction wheels upon the second men-

tioned shaft having yieldable rims in direct frictional driving contact with the abrading medium.

4. In an abrading machine of the class described, a body, a roll rotatably mounted upon the body, a second roll rotatably mounted upon the body in spaced relation to the first mentioned roll, an abrading belt trained

about the rolls, means for adjusting the last mentioned roll, and friction means upon the body having frictional driving contact with the said abrading medium at its portion which is in engagement with the first mentioned roll.

In testimony whereof I affix my signature.
HAROLD A. SWAN.
